UNITED STATES PATENT OFFICE.

ALBERT H. MUELLER, OF PACIFIC, MISSOURI.

DESIGN FOR A TIRE.

Application filed February 27, 1925. Serial No. 12,501. Term of patent 14 years.

To all whom it may concern:

Be it known that I, ALBERT H. MUELLER, a citizen of the United States, residing at Pacific, in the county of Franklin and State of Missouri, have invented a new, original, and ornamental Design for a Tire, of which the following is a specification, reference being had to the accompanying drawing, forming a part thereof.

I claim:—

The ornamental design for a tire as shown.

ALBERT H. MUELLER.
